UNITED STATES PATENT OFFICE

CLIFFORD OLDER, OF WILMETTE, ILLINOIS

PAVEMENT JOINT PROTECTOR OR TRAFFIC MARKER

Application filed June 7, 1929. Serial No. 369,021.

The present invention relates to pavement joint protectors, and is particularly concerned with joint protecting devices which may also be used, if desired, for traffic markers.

In the construction of concrete pavements or the like, it is a common practice to separate the pavement into longitudinal strips or sections for the purpose of preventing unsightly longitudinally extending cracks which inevitably appear when the pavement is laid in unbroken widths of more than ten or twelve feet.

The adjacent sections of concrete are tied together by embedding steel reinforcement in the concrete and the joints or cracks formed between adjacent sections of pavement are ordinarily filled with bituminous material such as asphalt or tar for the purpose of preventing the entry of water and dirt into the joints and to protect the edges of the concrete as much as possible.

The concrete pavements of the prior art have many disadvantages for the following reasons. It is practically impossible to provide a plastic filler such as tar or asphalt, which is sufficiently plastic and ductile so that it will not crack and allow dirt to enter the joint at any temperature and yet be stiff enough to prevent the admixture of roadway dirt, sand, grains, etc. Furthermore, the plastic material is forced out of the crack or joint by the heavy compression when the top surface of the pavement expands, and the constant necessity of renewing the filler from time to time as the traffic wears it away, involves much expense. The use of plastic filler for closing joints and protecting the edges is therefore very unsatisfactory.

The ordinary concrete pavement joints of the prior art are also unsatisfactory on account of the destructive results of unequal expansion and contraction of the upper and lower portions of the concrete pavement.

Assuming that the concrete pavement has been warmed by long exposure to the sun, as might be the case on any relatively warm day, when the temperature falls at night, the top surface of the concrete will cool first and contract more than the bottom surface. This

causes an upward warping of the edges of the concrete adjacent to the crack or joint, and, of course, adjacent any other edge or corner, and the reinforcing tie bars will be stretched, probably within their elastic limit, but the tie bars may slip or even partially fail by the tension if the cross section of steel is not properly proportioned to that of the concrete.

The concrete near the bottom of the slab may then yield slightly, but the upward warping of the edges of the concrete sections causes the edges of the concrete to be crushed at the bottom of the pavement between the sections.

At the same time the crack is considerably widened at its top due to the warping of the concrete sections and the unequal contraction at the top surface so that while the pavement is in this condition, dirt or soil may readily enter the top of the crack and become more or less packed therein by traffic.

Assuming that the concrete pavement is relatively cool as it would be in the morning, when the temperature of the air quickly rises above that of the body of the concrete, and the top of the concrete is in addition heated by the direct rays of the sun, to a temperature higher than that of the bottom surface, a reverse action of unequal expansion takes place. That is, the top surface expands at a greater rate than the lower surface and the top edges come together or in contact with the incompressible dirt or sand particles that have found their way into the crack or joint, and the pressure at the top edge is sufficient to cause the top edges to crush, chip or spall, and this destructive action continuing from day to day and combined with that of traffic, soon causes the edges of the concrete sections to become so chipped that the interior concrete surface is exposed and the destructive effects of traffic and temperature are thereby greatly increased.

One of the objects of the present invention is the elimination of the foregoing difficulties and others, by the provision of a metal joint protector which is capable of permitting expansion between the adjacent sections

of concrete and which is also capable of overlying and protecting the adjacent edges of the concrete sections.

Another object of the invention is the provision of a concrete pavement joint protector which is also capable of use as a traffic marker, and which is capable of long service without any substantial expense in maintenance or repair.

Another object is the provision of a concrete joint protector which is cheaply manufactured and economically installed, and which is capable of being kept in good condition by the effect of the traffic itself.

Another object is the provision of a traffic marker which is capable of use for marking traffic lines for either automobiles or for pedestrians, and which provides a contrasting appearance which is plainly visible under any light or weather conditions.

Another object of the invention is the provision of an improved concrete pavement joint including a pavement joint protector and traffic marker, and an improved form of aligning means for preventing settling of one concrete section relative to another.

Other objects and advantages of the invention will be apparent from the following description and from the accompanying drawings, in which similar characters of reference indicate similar parts throughout the several views.

Referring to the drawings, of which there are two sheets;

Fig. 1 is a plan view of a joint protector or traffic marker constructed according to the present invention;

Fig. 2 is a side elevational view of the same;

Fig. 3 is a transverse sectional view of a pavement joint constructed according to the present invention, in which the crack is produced by the use of a trowel or other tool;

Fig. 4 is a similar view of a modified joint construction in which a simple division plate is used for producing a plane of weakness which will form the crack desired;

Fig. 5 is a similar view of a modified joint construction using a division plate which is provided with a doweling means;

Fig. 6 is a similar view of a modified form of pavement joint having a different form of parting strip;

Fig. 7 is a similar view of a modified form of joint having a different parting strip;

Fig. 8 is a similar view of another modification having a parting strip which is provided with means for maintaining the alignment of adjacent sections of the pavement.

Referring to Figs. 1 to 3, 10 and 11 indicate adjacent sections of concrete pavement having adjacent edges 12 and 13 forming a crack 14 which is adapted to be protected by the concrete joint protector indicated in its entirety at 15. The crack 14 may, of

course, extend longitudinally of the pavement where it is desirable to separate a wide pavement into strips in which case the joint protector 15 will act as traffic markers, defining lines for the automobile traffic. The joint protectors 15 are also capable of use on joints extending in any other direction, as, for instance, upon transverse joints such as might be desirable for marking lanes of traffic for pedestrians, or the joint protectors 15 may be employed between adjacent sections of concrete where it is only desired to protect the edges of the concrete and there is no necessity for traffic marking.

The joint protector 15 preferably comprises an elongated sheet metal member which is formed with a flexible portion 16 which is adapted to give to permit expansion or contraction of the adjacent sections of concrete 10 and 11 and the flexible portion 16 may comprise a longitudinally extending rib of substantially V-shape, forming a groove tapering in width from the top of the groove to the bottom of the V. The rib 16 may in some embodiments of the invention be made thinner than the adjacent portions of the joint protector in order to increase the flexibility and the rib is preferably provided with rounded corners or bends in order to eliminate any possibility of breaking of the metal.

The joint protector 15 is preferably made of sufficient width to overlap or overlie several inches of the concrete sections 10 and 11 on each side of the crack 14 so that any pressure which is brought to bear on the joint protector 15 is distributed over a considerable area of concrete, and there is no possibility of the concrete immediately adjacent the crack 14 becoming exposed, even if its edges should become chipped, which is not likely in view of the protection provided.

The rounded upper corners of the concrete sections 10 and 11 formed by the V-shaped rib 16 also tends to prevent any chipping of the upper corners when the concrete expands or contracts.

The joint protector 15 is preferably formed with downwardly turned flanges 17 at the outer edges of the joint protector, the flanges 17 being curved downward into the concrete to positively prevent the formation of any ragged metal edges which might injure tires or which might spring up and down under the traffic. The downwardly turned curved flanges 17 also aid in anchoring the joint protector in place, and these flanges may be considered as anchoring formations in certain of the embodiments of my invention.

The joint protector 15 is also preferably provided with a plurality of anchoring formations 18 for the purpose of positively anchoring the metal plate in both concrete sections, and the anchoring formations 18 may take any of a plurality of different forms.

The formations 18 are preferably so shaped that the embedded portions 19 are of greater size than the intermediate portions 20 which connect the embedded portions 19 to the body 5 of the plate 15 so as to prevent withdrawal of the anchoring formations 18 from the concrete after it has set, and the embodiment chosen to illustrate the invention comprises a substantially T-shaped anchoring formation 18 with the top of the T embedded in the concrete.

I desire it to be understood that the anchoring formations 18 may be made of any ornamental or desirable appearance, such as 15 tongues of tapering width, curved strips, etc.

In order to save material and to provide means for determining when the joint protector has been properly placed in the concrete, I prefer to form the anchoring formations 20 by punching the same out of an integral part of the body of the plate 15, leaving apertures 19 of a shape complementary to the anchoring formations 18, and the apertures 19 permit the pavement to be visible through 25 the concrete plate 15 so that the plate may be pushed down into proper position after the concrete has been finished. The apertures 19 also permit the ready escape of air which might otherwise be trapped, and provide a 30 ready means of visually determining that the under surface of the joint protector is in contact with the upper surface of the concrete.

As previously stated, the pavement is preferably substantially finished before the joint protector is put in place and the cracks 14 may be formed in any of a plurality of different ways.

Referring to Fig. 3, the crack 14 has been 40 formed in this embodiment by cutting the concrete longitudinally with a trowel or other suitable means, thereby providing an opening of appreciable width. The adjacent sections 10 and 11 in this embodiment are tied together by a stirrup shaped tie member 20, comprising a rod bent to substantially U-shape, driven into the soil and covered with concrete.

Referring to Fig. 4, the crack 14 in this 50 embodiment has been formed by the use of a parting strip 21 comprising an elongated strip of sheet metal having slots or apertures 22 for receiving the stirrup or tie bar 20. The crack 14 is formed when the concrete sections 55 10 and 11 contract, due to the plane of weakness formed by the parting strip 21.

Referring to Fig. 5, the joint protector is 60 here illustrated in conjunction with a parting strip 23 comprising a sheet metal member having a longitudinally extending rib 24 for forming an aligning projection 25 upon the concrete section 11 and a complementary recess 26 upon the concrete section 10. The parting strip 23 may be secured in place by pegs or sticks 27 driven through the rib 24

and the sections may be tied together by the stirrups 20 passing through apertures or slots in the parting strip 23.

Referring to Fig. 6, the parting strip of 70 this embodiment comprises an elongated strip of sheet metal 28 having a laterally bent flange 29 at its upper edge for engagement and definitely locating the joint protector 15 at the point at which the crack will be formed. The parting strip 28 may be supported upon the stirrups 20 and may be put in place during the pouring of the concrete.

Referring to Fig. 7, the parting strip 30 of 75 this embodiment is provided with a laterally projecting flange 31 for locating the joint protector 15 and with a longitudinally extending rod 32 about which the lower edge 33 of the parting strip 30 is curled. The rod and curled flange 33 provide a formation upon the parting strip which is capable of preventing relative vertical movement of the adjacent concrete sections.

Referring to Fig. 8, the preferred embodiment illustrated in this figure comprises a parting strip 33 having a laterally projecting 80 flange 34 for locating the joint protector 15 and having a plurality of oppositely extending loops 35, 36 for supporting a doweling means 37. The loops 35 and 36 may be formed by providing transverse slits 38 at 85 regularly spaced intervals and bending the metal outward in opposite directions on each side of the slit to a shape capable of receiving the doweling member 37.

The doweling member 37 preferably comprises a steel bar or plate having upper and lower plane surfaces capable of being slidably received in the complementary recess formed in the concrete sections 10 and 11 and the doweling member 37 is threaded through the 100 loops 35 and 36. The parting strip 33 of this embodiment is also supported upon the stirrup 20 and it should be noted that in each of the embodiments, the stirrup 20 permits the location of the parting strip at any of a plurality of positions. For instance, the stirrup 105 20 may be driven in any of a number of different positions with its upper portion still in place to support the parting strip 33 at the desired location, and no difficulty is experienced in locating the parting strip at the desired location where stony ground is encountered.

It will thus be observed that I have invented a joint protector which is capable of 120 use as a traffic marker, and which is adapted to protect the upper and adjacent corners of the concrete pavement in such manner that practically no maintenance expense is involved. The present traffic marker may be 125 constructed of non-corrodable metal if desired, but where sufficient traffic is encountered, the traffic markers will be kept in smooth and polished condition by the traffic itself, and the contrast between the smooth metal 130

surface and the dimmer pavement is sufficient under any light or weather conditions to render the marker plainly visible.

The improved form of concrete joint shown in the preferred embodiment is also capable of preventing any relative settling between the adjacent concrete sections, and the present construction may be installed with a minimum cost of material and labor.

13 While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. A traffic marker for concrete pavement and the like, comprising a sheet metal member having a longitudinally extending flexible portion and having downwardly turned border flanges for engaging in the pavement, and integral anchoring formations formed out of said metal member for securing the same to each of said sections, said flexible portion comprising a downwardly extending longitudinal rib of tapering width formed in said metal member.

2. In a concrete pavement joint, the combination of a pair of pavement sections with a division member comprising a metal strip between said sections, and a joint protector carried by said sections above said division member, said joint protector comprising a sheet metal member having a longitudinally extending flexible portion and having downwardly turned border flanges for engaging in the pavement.

3. In a concrete pavement joint, the combination of a pair of pavement sections with a division member comprising a metal strip between said sections, and a joint protector carried by said sections above said division member, said joint protector comprising a sheet metal member having a longitudinally extending flexible portion and having downwardly turned border flanges for engaging in the pavement, and integral anchoring formations formed out of said metal member for securing the same to each of said sections.

4. In a concrete pavement joint, the combination of a pair of pavement sections with a division member comprising a metal strip between said sections, and a joint protector carried by said sections above said division member, said joint protector comprising a sheet metal member having a longitudinally extending flexible portion and having downwardly turned border flanges for engaging in the pavement, and integral anchoring formations formed out of said metal member for securing the same to each of said sections,

said flexible portion comprising a downwardly extending longitudinal rib of tapering width formed in said metal member.

5. A division plate for concrete pavement sections comprising a strip of sheet metal having a plurality of oppositely bent loops formed in the same and an aligning member threaded through said loops.

6. A division plate for concrete pavement sections comprising a strip of sheet metal having a plurality of oppositely bent loops formed in the same and an aligning member threaded through said loops, said aligning member comprising a metal bar having upper and lower plane sides for slidably engaging in adjacent pavement sections.

7. A division plate for concrete pavement sections comprising an elongated metal strip having one edge curved about a reinforcing rod for providing an aligning member for adjacent concrete sections.

In witness whereof, I hereunto subscribe my name this 3 day of June, 1929.

CLIFFORD OLDER.
